Attorney

UNITED STATES PATENT OFFICE.

WILLIS E. TANNER, OF LEOMINSTER, MASSACHUSETTS, ASSIGNOR TO JOHN W. PICKERING, OF LEOMINSTER, MASSACHUSETTS.

BARRETTE.

Application filed July 5, 1922. Serial No. 572,975.

To all whom it may concern:

Be it known that I, WILLIS E. TANNER, a citizen of the United States of America, residing at Leominster, in the county of Worcester and State of Massachusetts, have invented certain new and useful Improvements in Barrettes, of which the following is a specification.

The present invention relates to new and useful improvements in barrettes and has for its primary object the production of a device of this character formed from a single strip of cellulose or closely analogous material.

A further object of this invention is the provision of this type of article of manufacture wherein the clasping arm or bar of the barrette is an integral part thereof and wherein the same is so bent or molded as to effectively clasp and rigidly hold any thickness of hair.

A still further object of the invention is the formation of the clasp bar so that the hair is clasped throughout the entire length of the body of the barrette thus overcoming any tendency of the hair to slip or become disengaged therefrom.

My improved device is so formed as to eliminate any hooks or hinges and thus obviate any liability of the hair to break or tear.

Other objects of the invention will appear as the nature of the invention is better understood, and the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of the device showing the clasp bar in closed and open positions, the latter position being shown in dotted lines,

Figures 2 and 3 are bottom and top plan views respectively of the device,

Figure 4 is a fragmentary cross sectional view of the clasp end of the barrette upon the line IV—IV of Fig. 2, and

Figure 5 is a transverse sectional view upon the line V—V of Fig. 2.

Referring more in particular to the several views, the present invention consists of a single strip of cellulose or the like

material molded to provide an arched backing or base member 1, curled at one end to provide a loop portion 2 which has integrally connected therewith the clasp bar 3 which is so arranged as to normally diverge downwardly from the bottom wall of the upper arched base portion 1, when the same is in its unlocked position.

Further the bar or clasp member 3 is so arranged or bent as to provide an inwardly formed hump portion 4 adapted to lie closely adjacent the inner wall of the backing 1 at a point slightly spaced from the curled end 2. From this hump portion 4 the bar 3 is formed upon an arc of a lesser degree than the arc of the backing 1 and lies in a plane from this point 4 to its opposite end 5 substantially parallel to the backing 1, when the same is in its closed position. It will thus be seen that by so forming this clasp bar 3 the hair of the user will be retained within a space substantially the entire length of the barrette.

The end of the arched backing 1 opposite from the curled end 2 is bent upon itself at 6 so as to provide a retaining finger or hook 7 spaced beneath this end of the backing 1 for the reception of the free end 5 of the locking bar or clasp 3. As clearly shown in Figs. 4 and 5, this finger or hook member 7 is dished or arched, so as to provide raised side portions 8, effecting abutments for the end 5 of the clasp bar 3 and thus effectively preventing disengagement of this locking bar when the same is engaged within the finger 7. It will be clearly seen that when the clasp bar is moved into a locking position the free end 5 will normally tend to lie substantially midway between the ends 8 of the finger 7, in which locked position the hair will be firmly retained between the adjacent walls of the backing 1 and the said bar 3.

While there is herein shown and described the preferred embodiment of the present invention it is nevertheless to be understood that minor changes may be made therein without departing from the spirit and scope of the invention as claimed.

What is claimed as new is:

A barrette formed of a single strip of cellulose material and comprising an arched backing member bent upon itself at one end so as to provide a loop or eye portion at this end, the said loop portion being positioned

heneath the arc of the said backing member and substantially inwardly of its end, a locking bar of lesser width than the width of said backing member, formed integrally with said loop portion, the said locking bar being provided with a hump portion adapted to lie closely adjacent the inner wall of said backing member at a point slightly spaced from said loop, the opposite end of 10 said backing member being also bent upon

itself to provide a retaining finger for the free end of said locking bar, the said retaining finger being arc-shaped in cross section with its inner concaved surface forming a dish or pocket for preventing the disengagement of the free end of the locking bar therewith. 15

In testimony whereof I affix my signature.

WILLIS E. TANNER.
